DESIGN FOR A FOLDING CRIB

Walter R. Horton, Venice, Calif.

Application March 16, 1946, Serial No. 127,602

Term of patent 3½ years

(Cl. D5—5)

To all whom it may concern:

Be it known that I, Walter R. Horton, a citizen of the United States, residing in Venice, in the county of Los Angeles and State of California, have invented a new, original, and ornamental Design for a Folding Crib, of which the following is a specification, reference being had to the accompanying drawing, forming part thereof.

Fig. 1 is a top plan view of a folding crib, showing my new design in open position.

Fig. 2 is a front elevational view.

Fig. 3 is a transverse section midway of Fig. 2.

Fig. 4 is a perspective view, showing the crib in a folded position.

I claim:

The ornamental design for a folding crib, substantially as shown.

WALTER R. HORTON.
